UNITED STATES PATENT OFFICE.

SAMUEL R. BAILEY, OF AMESBURY, MASSACHUSETTS.

CARRIAGE-SPRING.

SPECIFICATION forming part of Letters Patent No. 681,093, dated August 20, 1901.

Application filed May 10, 1901. Serial No. 59,546. (No model.)

To all whom it may concern:

Be it known that I, SAMUEL R. BAILEY, a citizen of the United States, residing at Amesbury, in the county of Essex and State of Massachusetts, have invented new and useful Improvements in Carriage-Springs, of which the following is a specification.

This invention relates to improvements in carriage-springs for vehicles; and it relates to improved means for connecting the ends of the leaf or elliptic springs, as will herein-after be more fully shown and described, reference being had to the accompanying drawings, wherein—

15 Figure 1 represents a side elevation of a carriage-spring, showing its ends connected by my improved device. Fig. 2 represents an enlarged top plan view of one of the ends of the upper spring and its connection to the 20 end of the lower spring. Fig. 3 represents a side elevation of Fig. 2. Fig. 4 represents a central longitudinal section on the line 4-4 shown in Fig. 2. Fig. 5 represents an end view seen from X in Fig. 3. Fig. 6 represents a detail perspective view of one end of the lower spring.

Similar letters refer to similar parts wherever they occur on the different parts of the drawings.

30 In Fig. 1, A and B represent, respectively, the upper and lower leaves of an elliptic or leaf vehicle-spring, to which are respectively attached the additional leaf-springs *a a a* and *b b b*, as is usual in this kind of carriage-springs. At each end of the spring A is made a hooked lip A', adapted to receive the end of the other spring B, as shown in Figs. 3 and 4. In the hooked end of the spring A is made a slotted perforation A'', through which is inserted a shank B', made integral with the end of the spring B, as shown in Figs. 4 and 6. The said shank B' is provided at its end with a hooked head or projection B''. (Shown in Figs. 4 and 6.)

45 As shown most clearly in Fig. 6 of the drawings, the shanks B' are of much less width than the spring B, and the ends of the latter when the headed shanks are inserted in the apertures A'' in the spring A are received and retained by the hooked lips A'. The hook-shaped heads B'' project through

the apertures A'' and engage or hook over the walls of the latter, as shown most clearly in Figs. 3 and 4 of the drawings. The springs are thus doubly interlocked or hooked together at each end, the hooked lips A' hooking over the ends of the spring B and the hook-shaped heads B'' hooking over the walls of the apertures A'' in the spring A. The two springs are thus very securely connected together in such manner as to effectually prevent their becoming detached from each other and also preventing one of said springs from moving laterally relative to the other due to the jolting of the vehicle or similar causes. Furthermore, in springs of this character when the springs are compressed and suddenly expand as the vehicle rebounds the spring B has a tendency to slip from out the hooked ends of the spring A; but in the present invention this is effectually prevented by the hook-shaped heads B'', which engage the walls of the apertures A'' in the spring A.

It is immaterial which of the springs is termed the "upper" or the "lower" one, as the device may be reversed in position without departing from the essence of my invention.

What I wish to secure by Letters Patent and claim is—

The herein-described elliptic carriage-spring comprising an upper and a lower member, one of said members having hook-shaped ends adapted to receive the ends of the other member, and the latter provided at its ends with shanks terminating in hook-shaped heads, said shanks passing through apertures in the said hook-shaped ends and the hook-shaped head engaging the ends of the apertured member, whereby the hooked ends of each member engage and interlock with the ends of the other member, thereby providing a duplex connection between the springs at each end of the latter, substantially as described.

In testimony whereof I have hereunto set my hand in presence of two subscribing witnesses.

SAMUEL R. BAILEY.
